[57] CLAIM

The ornamental design for a instrument housing for a
ski pole, as substantially shown and described.

DESCRIPTION

FIG. 1 is a right front perspective view of an instrument
housing for a ski pole showing my new design, the
broken-lines being environmental only and forming no
part of the claimed design;

FIG. 2 is a right side elevational view thereof;

FIG. 3 is a top plan view thereof;

FIG. 4 is a bottom plan view thereof;

FIG. 5 is a front elevational view thereof;

FIG. 6 is a rear elevational view thereof.
